CLAIM

The ornamental design for a riding saddle, as shown and described.

DESCRIPTION

FIG. 1 is a right side elevational view of a riding saddle, showing my new design;

FIG. 2 is a left side elevational view thereof;

FIG. 3 is an enlarged rear elevational view thereof;

FIG. 4 is an enlarged front elevational view thereof; and,

FIG. 5 is a top plan view thereof, with the saddle laid out flat.
